Filed Nov. 29, 1965, Ser. No. 510,225
20 Claims. (Cl. 204—98)

This invention relates to chlor-alkali diaphragm cells and more particularly to a method of operating chlor-alkali diaphragm cells alone or in groups under controlled conditions of pH, anolyte salt concentration and temperature, to thereby increase the efficiency of such cells, to control the proportions of chlorine and caustic soda produced, to reduce anode consumption, to produce a cell liquor of increased caustic soda content and to effect numerous other improvements in cell operations, as hereinafter disclosed.

Chlor-alkali diaphragm cells have for years been run in large groups of 50 to 100 or more cells, each cell running independently of the other cells. The products from these cells were combined into three major effluent streams so that the total groups of cells produce an effluent stream of chlorine, an effluent stream of hydrogen and an effluent stream of cell liquor. The cell liquor was a mixture of about 9 to 12 weight percent caustic and about 10 to 18 weight percent salt.

With each cell running individually, only very limited control could be maintained on the operation of the cell such as could be achieved through changes in the decomposition voltage and regulation of the brine concentration and feed rates which in turn, depended largely on the porosity and flow rate through the diaphragm. This resulted in each cell operating at different efficiencies and under different conditions of temperature, anolyte concentration, pH, and so forth. As an example, cells having new anodes maintain an operating temperature which is lower than the most efficient operating temperature. In turn, cells having old, worn anodes tend to operate at temperatures above the most efficient operating temperature and often result in the expenditure of excessive amounts of current in heating the electrolyte to its boiling point.

The major items of expense in operating diaphragm cells are (1) power, (2) cell renewal and (3) caustic evaporation. All of these items are directly related to the cell operation in (1) current efficiency, (2) cell voltage, (3) anode life, (4) diaphragm life and (5) cell liquor caustic and salt concentration. If the current efficiency and cell voltage could be advantageously controlled to reduce power costs and extend the anode life, and if the diaphragm life could also be extended, two of the major cost items in operating diaphragm cells would be reduced. Further, if in advantageously controlling the first four factors enumerated above, the cell liquor caustic and salt concentrations could be changed to a more advantageous ratio, then all three of the major cost items in operating diaphragm cells could be reduced, thereby greatly improving chlor-alkali diaphragm cell operations.

It is an object of this invention to provide a method whereby the current efficiency of chlor-alkali diaphragm cells is improved. It is another object of this invention to provide a method whereby chlor-alkali cell voltages are advantageously improved to operate at the most efficient level. A further object of this invention is to provide a method whereby the anode life of chlor-alkali diaphragm cells is extended. Yet, another object of this invention is to provide a method of operation whereby the porosity of the diaphragm becomes less critical, so that the diaphragm life can be extended to equal the anode life. Another object of this invention is to improve the caustic-salt con-

centration ratio in the cell liquor by producing a higher concentration of caustic in the cell liquor. These and other objects will become apparent to those skilled in the art from the description of the invention which follows.

In accordance with the invention, a process is provided for operating a group of chlor-alkali diaphragm cells comprising imposing a decomposition voltage across the electrodes of a group of chlor-alkali diaphragm cells, feeding a solution of brine to the anolyte compartments of each of said cells at a rate in excess of the amount which flows through the diaphragm of said cells, withdrawing the excess brine feed solution from the anolyte compartments of said cells, combining and replenishing the withdrawn solutions with additional amounts of salt and returning the replenished anolyte brine solution to the anolyte compartments of said cells. Preferably, the feed brine is a saturated or nearly saturated solution. In this anolyte recirculation method, the feed rate of brine to the anolyte compartment is greater than the amount which flows through the diaphragm and preferably is in an amount greater than one time and up to about ten times the amount which flows through the diaphragm into the catholyte compartment. In addition to operating a series of cells with the brine feed in parallel, the process can also be readily effected with each cell on an individual basis. Even further, improvements are obtained wherein temperature and pH adjustments, as by the addition of acid, are made with the anolyte solution in the cell.

The anolyte recirculation method of the present invention provides greatly improved control of the anolyte liquor to thereby provide the highest operating efficiencies in chlor-alkali diaphragm cells. The process can be operated with a group of cells, thereby establishing controlled conditions of temperature, anolyte pH, anolyte and cell liquor concentration, and the like, which are substantially the same in all of the cells, thereby effectively operating all or nearly all of the cells under the most desirable conditions.

The process of the present invention can be used in the electrolysis of any alkali metal chloride. However, because sodium chloride is preferred and is normally the alkali metal chloride used, the description hereinafter is directed more particularly to sodium chloride. It is to be understood, however, that other alkali metal chlorides can be used, particularly potassium and lithium chlorides.

The invention will be further described by reference to the drawings in which:

FIG. 1 is a partially schematic flow sheet illustrating the process of the present invention, particularly as it relates to operation of a group of cells;

FIG. 2 is a vertical, partial section of a typical chlor-alkali cell modified in accordance with the present invention;

FIG. 3 is a side elevation of FIG. 2 further showing a typical modification of the chlor-alkali cell; and

FIG. 4 is a graph showing the average relationship between cell liquor strength, current efficiency and rate of HCl addition for chlor-alkali diaphragm cells operated in accordance with the present invention.

It has been found that the anolyte salt concentration has an effect on the current efficiency. Normally, increasing the chloride concentration in the anolyte compartment results in benefits of higher current efficiency, purer chlorine, lower voltage, lower graphite consumption, higher caustic concentration and less chlorate in the cell liquor so that it is normally preferred to operate at the highest salt concentration. However, the solubility of sodium chloride in the feed brine limits the amount of sodium chloride which can be practicably fed to a normally operated cell.

Since both chlorine and sodium ions are being removed from the cell at the electrodes, the bulk anolyte solution

becomes depleted of salt to such an extent that a normal cell has an anolyte salt concentration considerably below the saturation point, even though the brine was fed to the cell as a nearly saturated solution. Typically, a normal diaphragm cell was fed with a brine solution containing about 320 to 330 grams per liter of sodium chloride (a saturated solution at about 90 degrees centigrade contains about 333 grams per liter) but has an anolyte sodium chloride concentration of only about 270 grams per liter. Better cell operation is obtainable at higher anolyte salt concentrations.

It has now been found that by the present anolyte recirculation method, the advantages of higher sodium chloride concentration in the anolyte compartment can be realized by feeding a stream of brine to the anolyte compartment at a rate faster than the brine can pass through the diaphragm into the catholyte compartment. Thus, it is possible to increase the sodium chloride concentration in the anolyte compartment by continuously adding concentrated brine and removing depleted anolyte solution. The excess brine is withdrawn from the anolyte compartment and is resaturated with sodium chloride. Also, it is preferred to adjust the temperature to the desired operating range and to add HCl in an amount to obtain the desired anolyte pH prior to returning the brine to the anolyte compartment. The practical over-all result is that a leveling effect is obtained in all of the cells and the sodium chloride concentration in the anolyte compartment is increased to a level higher than that previously obtainable. By the present method, the sodium chloride concentration in the anolyte compartment can be maintained at any level up to the saturation concentration and particularly may be maintained within the preferred range of 260 to 330 grams per liter of sodium chloride. Because the recirculation of the anolyte liquor without an enrichment of sodium chloride results in substantial improvements in the operation of chlor-alkali cells, the present invention can also be operated with lower NaCl concentrations, such as about 130 to 260 grams per liter of NaCl.

The process of the present invention is effected, as illustrated by FIG. 1, by feeding a concentrated stream of feed liquor 10 to a group of chlor-alkali diaphragm cells 16 by means of lateral feed lines 12, 13, 14 and 15. The group or series of cells may be 2 to 100 or more cells from which anolyte liquors are withdrawn and combined for recirculation. The feed rate of brine to the cells 16 by means of the lateral lines 12, 13, 14 and 15, is at a rate greater than the amount of liquor which flows from the anolyte compartment through the diaphragm in the chlor-alkali cell into the catholyte compartment and more preferably, the brine feed rate is 1.5 times up to about ten times the flow through the diaphragm. The most preferred flow rate averages, for a group of cells, is about two to five times that flowing through the diaphragm. The excess feed liquor is withdrawn from the cells 16 via lines 18, 20, 22 and 24. These lines are combined and returned to salt saturator 28 via line 26. Cell liquor 40 is withdrawn from the catholyte compartments of the cells via lines 35, 36, 37 and 38 using suitable withdrawal means.

In salt saturator 28, additional sodium chloride 30 and water 31, or mixtures thereof, are mixed with the brine to resaturate it with sodium chloride prior to returning the brine to the anolyte compartments of the cells 16 via line 10. Normal salt saturation techniques are used in the salt saturation step. In addition to resaturating the withdrawn anolyte liquor, sufficient additional brine is prepared or mixed with the anolyte liquor to replace brine which passes through the diaphragm in the electrolytic cell.

Another variable which affects the anode current efficiency is the anolyte temperature. The provisions for heat exchange means 32 associated with brine saturator 28, as shown, or other heating means, provide for main-

taining the cells at the most efficient operating temperatures. Heat exchange means 32 maintains the saturator 28 at the proper temperature for saturating the recirculating anolyte solution so that the maximum practical salt concentration is supplied to the cells. Normally, saturated brine fed to the cells contains about 26 to 27 percent NaCl by weight or about 327 grams per liter of NaCl, which is the saturation concentration at about 65 degrees centigrade. Additional heat is provided after the saturator to superheat the brine to a temperature of approximately 75 to 80 degrees centigrade to prevent the deposition of salt crystals in the feed lines to the cells. This latter temperature (superheat) is regulated so that the temperature of the anolyte in the cell is maintained between about 85 and 100 degrees centigrade by the additional heat provided by the electrochemical reaction taking place in the cell.

Alternatively, the saturator can be operated at a higher temperature, such as 75 to 80 degrees centigrade, and a small stream of unsaturated brine or water may be added after the saturator to reduce the salt concentration in the brine to about 327 grams per liter to prevent salt drop out in the lines to cell. Again it is preferred that the temperature of the saturated brine to cell be regulated so that the operating temperature in the anolyte compartment of the cell is maintained at the most preferred temperature of about 93 to 100 degrees centigrade.

In an operating group of electrolytic cells, the amount of heat required by heat exchanger 32 varies primarily with the requirements to heat the additional water or brine added in the salt saturator 28. The heating of brine prior to feeding it to the cell is not in itself, new. However, the effect of rapid anolyte turnover and the mixing of the anolyte effluents from a group of cells produces a cumulative heat exchange effect which results in all of the cells operating at more efficient temperatures independent of the cell age, electrode decomposition, particular cell characteristics and the like factors which previously dictated the individual cell operating temperature.

As a result of the changes effected in the anolyte compartment by means of the present anolyte recirculation method, further beneficial changes result in the entire cell operation. It was previously known that the addition of hydrochloric acid to a chlor-alkali diaphragm cell having a porous asbestos diaphragm resulted in a tightening of the diaphragm and a restriction of liquid flow through the diaphragm when the anolyte pH dropped to too low a level. When this occurred, the liquid level in the anolyte chamber increased and often the cell would have to be removed from service due to the high level. Because of the variations in porosity of deposited diaphragms and the changes effected by acid additions, the flow rates through the diaphragms varied with each cell such that previously the brine feed had to be individually controlled in each cell to maintain the desired cell liquor strength to compensate for the added acid. To regulate the anolyte pH within the most desirable pH range of 2 to about 4 while maintaining a proper cell level was indeed, a difficult task. To further complicate the matter, changes in the flow through the diaphragm affect the back migration of hydroxyl ions which changes the acid requirement for each cell. Thus, as a practical matter, large acid additions have not previously been feasible in large scale operations.

The present method of anolyte recirculation substantially reduces the need for individual cell attention due to changes in diaphragm porosity, hydroxyl ion back migration, and the like. The rapid anolyte turnover or flow rate produces a leveling effect in all the cells, whereby the desired pH range is maintained independent of the particular porosity of the diaphragm and back migration. In addition, the effects of a restricted diaphragm are of lesser importance because the anolyte recirculation method maintains the same anolyte liquid level independent of the flow through the diaphragm.

In a preferred embodiment of the present invention, hydrogen chloride 34 is added to the saturated or nearly saturated brine withdrawn from salt saturator 28 via line 10. When HCl is added, it is added in an amount sufficient to maintain an anolyte pH within the range of about 0.2 to about 4.5 and more preferably about 1.5 to 4. The most preferred pH range is about 2.0 to 3.0. The lowest pH values are best used with a diaphragm material other than asbestos, such as chlorinated polyvinyl chloride, polypropylene, and the like. The amount of HCl required for this adjustment varies with the particular operating conditions and can be in amount up to about 20 percent HCl based on the amount of chlorine liberated at the anode; that is, 20 percent of the chlorine produced is from the HCl addition. With greater amounts of HCl being added, the pH of the brine fed to the cell can be as low as about 0.2. When no HCl is added, the pH of the brine fed to the cell is as high as about 7, because the recirculated anolyte lowers the brine pH from the normally alkaline pH of about 9 to a neutral or slightly acidic pH. The HCl added can be added either as a gas or as an aqueous solution.

The pH of the anolyte has been found to be important in establishing high current efficiencies in the cell, and especially in attempting to improve the efficiency of already highly efficient cells. In normal cell operations, the back migration of the hydroxyl ions into the anolyte results in an increase in the anolyte pH while the chlorine evolved therein lowers the pH. Cells running individually will vary widely in anolyte pH. Normally, a low anolyte pH is obtained in cells with new diaphragms and a high anolyte pH is found in cells with older diaphragms. As the mechanism of back migration of hydroxyl ions is presently understood, the migration increases for any particular diaphragm as the concentration of caustic in the catholyte cell liquor increases. In turn, the concentration of caustic in the catholyte cell liquor increases because of a decrease in the flow of brine into the catholyte chamber as a result of a decrease in the porosity of the diaphragm. The decrease in the diaphragm porosity results from the deposition of calcium and magnesium compounds and other substances in the diaphragm pores during use. Thus, over-all brine quality and the nature of the diaphragm are factors which bear significantly on the changes in anolyte pH and its attendant lower cell efficiency.

In normal cell operation, when the anolyte pH increases for any reason, there is no built-in compensating effect to keep it at its proper value. The present invention provides the means for maintaining anolyte pH within the desired range by (1) recirculating the anolyte from a group of cells to obtain the cumulative effect of the anolyte pH of all of the cells so as to result in the cells operating at a pH which is the average thereof and/or by (2) the addition of HCl to the brine feed, with anolyte recirculation. Thus, the cell can always be kept operating at the most effective pH for peak efficiency substantially independently of the porosity of the diaphragm and the concentration of the caustic in the catholyte chamber.

Being able to use a tight diaphragm or a diaphragm of lower porosity has the added benefit of enabling cell operation at higher caustic concentrations in the catholyte compartment. Whereas previously the catholyte solution (cell liquor) contained about 9 to 12 percent sodium hydroxide, caustic concentrations can now be in the range of 12 to about 22 percent in the catholyte cell liquor or about 145 to 270 grams per liter of NaOH, while the desired anolyte pH is maintained. As will be readily realized, the process can also be operated to obtain normal cell liquor strengths of about 110 to 150 grams per liter of NaOH. By controlling the anolyte pH at the desired efficient operating level, such as by increasing the recirculation rate and/or using brine with enough HCl dissolved in it to compensate for increased back migration of the hydroxyl ion, the former limiting

factor of the hydroxyl back migration is mitigated. By operating the cells to increase the caustic concentration in the catholyte compartment a higher ratio of caustic to sodium chloride in the cell liquor is obtained. Thus, over twice the normal caustic concentration can be obtained in the cell liquor, thereby greatly reducing the evaporation and concentration costs normally otherwise incurred.

FIG. 2 and FIG. 3 illustrate a chlor-alkali diaphragm cell modified so as to utilize the present anolyte recirculation method. A typical cell 44 having an anolyte compartment 46 separated from a catholyte compartment 48 by means of a porous diaphragm 50 is used. Catholyte compartment 48 has an overflow means 49 by which cell liquor is withdrawn from the cell. Within the anolyte compartment 46 are brine feed means 52, chlorine gas removal means 54, anodes 56 and anolyte liquid withdrawal means 64. Attached to the anolyte compartment is sight glass 60 which shows the level of anolyte liquor within the anolyte compartment.

Anolyte liquor withdrawal means 64 preferably has means for regulating the anolyte liquid level 62. Anolyte liquor withdrawal means 64 is thus preferably a passageway for liquids which is capable of being rotated about an axis passing through hole 66 through which anolyte withdrawal means 58 is attached. Thus, anolyte liquid level 62 can be changed to increase or decrease the hydrostatic head within anolyte compartment 46, as may be preferable when increasing or decreasing the caustic concentration in the catholyte compartment. Handle 68 is provided to aid in rotating anolyte liquor withdrawal means 64 when adjusting the anolyte level 62.

It is obvious that numerous modifications can be used to provide anolyte withdrawal means from the anolyte compartment. Such modifications can be either with or without anolyte liquid level adjustment means. An example of other adjustment means is an externally mounted inverted U tube which could be rotated to change the liquid level within the cell. Also, means similar to those used in regulating the catholyte liquid level could be used. Such other modifications will be readily apparent to those skilled in the art from the description herein.

Anolyte liquor withdrawn from anolyte compartment 46 by means of withdrawal means 58 is passed into stack 70 for return to the resaturator. Stack 70 has transparent sight glass 72 therein whereby the anolyte effluent liquor can be observed.

The following examples illustrate certain preferred embodiments of the present invention. Unless otherwise indicated, all parts and percentages used herein are by weight and all temperatures are in degrees centigrade.

EXAMPLE 1

A group of 23 Hooker type S-1 cells was operated in the normal method by feeding brine to the anolyte compartments of each cell at a feed concentration of 310 grams per liter of NaCl. The brine feed was at a pH of 9, which is the normal brine pH of feed liquor. A decomposition voltage of about 4 volts at about 12,000 amperes per cell was passed through the cells in the normal manner thereby producing gaseous chlorine at the anode and hydrogen and caustic soda (cell liquor) at the cathode. The caustic soda was withdrawn from the catholyte compartment of each cell as cell liquor. The group of cells was continuously operated for several weeks, during which time the operating conditions of the cells were noted. The brine feed rate during the period of operation averaged 2.7 liters per minute per cell which corresponds to the flow through the diaphragm of each cell. It was found that the average current efficiency of the cells for this period was 95.5 percent and that the anolyte temperature within the cells varied from cell to cell within the range of 92 degrees centigrade to 104 degrees centigrade, the average being about 95 degrees centigrade. The brine

strength within the anolyte compartments averaged 260 grams per liter of sodium chloride.

A similar group of 23 Hooker type S-1 cells was operated in accordance with the present invention wherein the cells were fed a brine solution in parallel, as shown in FIG. 1, at a rate in excess of the flow through the diaphragm and where the excess anolyte liquor was withdrawn, as shown in FIG. 1, using the anolyte liquor withdrawal means illustrated in FIGS. 2 and 3. Again, these cells were fed with a brine solution containing 310 grams per liter of sodium chloride but the feed rate was increased from the normal rate of about 2.7 liters per minute to about 7.0 liters per minute, or about an average of 2.5 to 2.75 times the flow through the diaphragms of said cells. The excess anolyte liquor, which varied slightly from cell to cell within the range of about 4 to 5 liters per minute, the average being about 4.3 liters per minute, was withdrawn from the cells, mixed together and resaturated to 310 grams per liter of NaCl prior to being returned to the anolyte compartments of the cells. Under these conditions, the sodium chloride concentration in the anolyte compartment averaged 295 to 300 grams per liter of sodium chloride. The pH of the anolyte liquor withdrawn from the anolyte compartments averaged 3.5 to 4.0. The resaturated and replenished brine returned to the cell had a pH of 6.5. The temperature within the anolyte compartments of the cells varied from 94 to 96 degrees centigrade, the average being 95 degrees centigrade. After extended operation, it was found that the group of cells using the anolyte recirculation method of the present invention had improved current efficiencies compared to the cells operated in a conventional manner. The average current efficiency of the cells operating by the anolyte recirculation method was 96.4 percent.

EXAMPLES 2-8

The method of the present invention was operated in accordance with FIG. 1 and the method described in the specification wherein cells modified as shown in FIGS. 2 and 3 were used, this method was compared with normal cell operations as in a production size operation. The comparison was made between a group of 10 standard 30,000 amperes Hooker type S-3 cells which produce about one ton of chlorine per cell per day and an equal number of S-3 cells modified as in FIGS. 2 and 3, which were operated in accordance with the present invention. Table I tabulates the average results obtained during an average

24 hour period under the noted conditions of operation. Table II illustrates the advantages to be gained in a commercial size plant producing 200 tons per day of chlorine based on six months of operation.

In Tables I and II, Example 2 illustrates the results obtained under conventional cell operations. Examples 3 through 8 show the results obtained utilizing the anolyte recirculation method of the present invention. Example 3 illustrates the cell operation without an HCl addition of Examples 4 through 8 illustrate the cell operation with HCl additions of varying percentages. The percentages of HCl addition noted are based by weight on the amount of chlorine produced by the cell.

The cell operating temperatures averaged about 95 degrees centigrade, varying from 94 to 96 degrees centigrade, for the anolyte recirculation examples. The operating temperatures of the standard Hooker type S-3 cells also averaged about 95 degrees centigrade, but the individual cells varied widely from about 92 degrees centigrade to about 100 degrees centigrade.

All of the cells were operated at 30,000 amperes. The brine feed rate to the standard S-3 cells averaged about 6.44 liters per minute. The brine feed rate to the anolyte recirculation Examples 3 through 8, averaged about 20 liters per minute, with the amount of withdrawn anolyte liquor ranging from about 13.5 to 17 liters per minute. The lesser withdrawal rate, i.e., about 13.5 liters per minute, was used in Examples 3 through 5 to correspond to a flow through the diaphragm about equal to that of Example 2, and the greatest withdrawal rate was used in Examples 7 and 8. The lesser flow rates through the diaphragm resulted in producing more concentrated caustic in the catholyte compartment. The particular flow rate for the cells used in the present method was regulated by changing the hydrostatic head in the anolyte compartment by means of the apparatus of FIGS. 2 and 3. Slight variations in the withdrawal rate were noted due to differences in diaphragm porosity.

All of the cells were fed with a nearly saturated brine containing about 315 grams per liter of sodium chloride at a feed temperature of about 80 degrees centigrade. The anolyte sodium chloride concentration for the cells of Example 2 was about 270 grams per liter whereas the cells of Examples 3 through 8 had sodium chloride concentrations between 280 and 310 grams per liter, the average being about 300 grams per liter.

Table I shows the results obtained as follows:

A comparative analysis of Example 2, which is the average of conventional cell operation, with the examples of the anolyte recirculation method as illustrated in Examples 3 through 8, shows that even without the addition of HCl to control the anolyte pH, improved results are obtained in current reduction, voltage reduction and a reduction in the percentage of cells renewed. With the addition of HCl, increased anode efficiency is noted in addition to markedly improved cell life. The current reduction and reduction in percentage of cells renewed is also markedly improved. By regulating the flow of brine through the diaphragm by raising or lowering the hydrostatic head in the anolyte compartment, the amount of sodium hydroxide contained in the cell liquor can be also changed so as to greatly improve the caustic salt ratio in the catholyte cell liquor. A decrease in the flow rate through the diaphragm, as by lowering the hydrostatic head, increases the caustic concentration in the catholyte compartment thereby increasing the demand for HCl to maintain the desired pH due to an increase in the back migration of hydroxyl ions through the diaphragm. Higher caustic concentration greatly reduces the amount of water to be evaporated to make 50 percent sodium hydroxide and reduces the amount of fresh feed brine to be heated. The economic advantages of the process are clearly illustrated in Table II.

As is seen from an examination of Tables I and II, the present method can be used to regulate the proportion of chlorine to sodium hydroxide produced. As has often been the situation, the demand for chlorine is greater than that of sodium hydroxide. Therefore, it is often preferable to produce more chlorine than caustic. This can readily be accomplished by the present invention.

EXAMPLE 9

This example illustrates the preferred operating conditions of the present invention under varied conditions of

efficiencies and the over-all effects of the anolyte recirculation method of the present invention. All of the examples utilized a brine feed having a sodium chloride concentration of 315 grams per liter. The cells were operated at 12,000 amperes. Example 10 shows the operation of a normal cell without anolyte recirculation. Example 11 illustrates the anolyte recirculation process of the present invention without acid addition, wherein the brine recirculation is at a rate of about 2.3 times that flowing through the diaphragm which corresponds to a feed rate of about 6.2 liters per minute, 3.5 liters of which were recycled. The withdrawn anolyte solution is resaturated and the temperature adjusted prior to returning the brine to the cell to provide an anolyte temperature of about 98 degrees centigrade.

Examples 12 through 14 employed the same recirculation method as in Example 11 but with a reduced hydrostatic head within the anolyte compartment to increase the caustic concentration in the catholyte compartment by reducing the flow through the diaphragm. At a feed rate of 3.6 liters per minute about 1.6 liters per minute of anolyte liquor were withdrawn from the anolyte compartment for recirculation. The reduced hydrostatic head reduced the flow through the diaphragm to about 2 liters per minute. The feed brine was acidified with HCl to a pH of 0.2, the amount of HCl added was chosen to provide the noted anolyte pH.

Examples 15 through 17 were run in the same general manner as Examples 12 through 14, but with the anolyte recirculation rate being about 1.5 times that flowing through the diaphragm into the catholyte compartment. This corresponded to a feed rate of about 3.3 liters per minute of brine of which about 1.1 liters per minute of anolyte liquor were withdrawn for recirculation, the remaining 2.2 liters per minute passed through the diaphragm into the catholyte compartment.

Example Number	Current Efficiency, Percent	Calculated cell life-days based on six months of operation	Anolyte pH at 25 degrees centigrade	Anolyte, grams per liter of NaCl	Cell liquor, grams per liter of NaOH
10.	95.2	250	3.8	240	140
11.	96.0	259	3.8	300	140
12.	96.0	375	2.7	279	252

¹ Not determined.

HCl additions and cell liquor caustic concentration. FIG. 4 shows the average relationship between cell liquor strength, current efficiency and rate of HCl addition for chlor-alkali diaphragm cells operated at an average anolyte temperature of 94 degrees centigrade and an anolyte recirculation rate sufficient to provide an anolyte NaCl concentration of 300 grams per liter at a feed concentration of 310 to 315 grams NaCl per liter. The data given in FIG. 4 are the averages obtained from numerous runs using Hooker type S-1 production cells operated in accordance with the invention at 12,000 amperes. Curve A illustrates the relationship between HCl additions and the amount of caustic which is retained in the cell liquor to obtain an anolyte pH at a level which will provide a 98 percent current efficiency. Changes in this relationship bring about corresponding changes in current efficiencies as is illustrated by curves B, C and D.

The illustrated curves are for constant conditions of anolyte temperature and anolyte sodium chloride concentrations. Changes in these conditions will displace or alter the slopes of the curves.

EXAMPLES 10-17

Individual Hooker type S-1 cells were operated in accordance with the present invention to determine the effects of high catholyte caustic concentrations on cell

50 As is readily recognized from a comparison of Examples 10 through 17, improved cell operation is obtained by the present method for a wide range of caustic concentrations when the anolyte pH is maintained below about 4.

55 While there have been described various embodiments of the present invention, the methods described are not intended to be understood as limiting the scope of the invention. It is realized that changes therein are possible and it is further intended that each element recited in any of the following claims is to be understood as referring to all equivalent elements for accomplishing substantially the same results in substantially the same or equivalent manner. It is intended to cover the invention broadly in whatever form its principles may be utilized.

We claim:

60 1. A process for operating a group of chlor-alkali diaphragm cells comprising imposing a decomposition voltage across the electrodes of said chlor-alkali diaphragm cells, feeding a solution of brine to the anolyte compartment of each of said cells at a rate in excess of the amount which flows through the diaphragm of said cells, withdrawing the excess brine feed solution from the anolyte compartments of said cells, combining and replenishing the withdrawn solutions with additional amounts of a chloride selected from the group consisting of an alkali metal chloride, hydrogen chloride and mixtures thereof,

and returning the replenished brine solution to the anolyte compartments of said cells.

2. The process of claim 1 wherein the temperature of the brine feed solution is adjusted to obtain an anolyte temperature of about 85 to 100 degrees centigrade.

3. The process of claim 1 wherein the brine feed solution fed to the cell contains 130 to 330 grams per liter of sodium chloride.

4. The process of claim 1 wherein the brine fed to the anolyte compartment is nearly saturated sodium chloride solution.

5. The process of claim 4 wherein the brine feed solution is fed to the anolyte compartment at a rate of 1.5 to about 10 times the rate at which the brine passes through the diaphragm into the catholyte compartment of the cell.

6. The process of claim 1 wherein acid is added to the brine feed solution in an amount to obtain an anolyte pH within the range of about 1.5 to 4.0.

7. The process of claim 6 wherein HCl is added to the brine feed solution in an amount to obtain an anolyte pH of about 2 to 3.

8. The process of claim 6 wherein the brine feed solution is acidified by the addition of up to about 20 weight percent HCl based on the amount of chlorine produced by the cell.

9. A process for operating a chlor-alkali diaphragm cell comprising feeding a solution of brine to the anolyte compartment of the chlor-alkali diaphragm cell while imposing a decomposition voltage across the electrodes of said cell, feeding said brine solution at a rate of about 1.5 to 10 times the amount which flows through the diaphragm of the cell into the catholyte compartment of the cell, withdrawing the excess brine feed solution from the anolyte compartment of the cell, replenishing the withdrawn solution with salt, adjusting the temperature of the solution to the desired feed temperature and returning the resaturated and adjusted brine solution to the anolyte compartment of the cell.

10. The process of claim 9 wherein the temperature of the brine feed solution is adjusted so as to obtain an anolyte temperature of about 93 to 100 degrees centigrade.

11. The process of claim 9 wherein the brine fed to the anolyte compartment contains about 280 to 330 grams per liter of NaCl and the rate of feed is sufficient to maintain an anolyte sodium chloride concentration in the anolyte compartment of about 280 to 330 grams per liter.

12. The process of claim 9 wherein the pH of the anolyte solution in the cell is maintained between about 1.5 and 4 by the addition of up to about 20 weight percent hydrogen chloride based on the amount of chlorine produced in the cell.

13. The process of claim 9 wherein the amount of anolyte feed solution passing through the diaphragm into the catholyte compartment is regulated by changing the level to which the anolyte liquor is withdrawn by adjustment of the anolyte liquor withdrawal means thereby changing the hydrostatic head within the anolyte compartment.

14. The process of claim 9 wherein the brine feed solution fed to the cell contains about 130 to 330 grams per liter of sodium chloride.

15. The process of claim 9 wherein the brine feed solution is a nearly saturated sodium chloride solution.

16. The process of claim 15 wherein said brine solution is fed to the cell at a rate of about 2 to about 5 times the amount which flows through the diaphragm of the cell into the catholyte compartment, the excess brine feed solution is withdrawn from the anolyte compartment and resaturated with salt, the temperature of the resaturated solution is adjusted to obtain an anolyte temperature of about 93 to 100 degrees centigrade, the acidity of the brine feed solution is adjusted by the addition of hydrogen chloride to obtain an anolyte pH of about 2 to about 3 and the resaturated and adjusted brine solution is returned to the anolyte compartment of the cell.

17. The process of claim 16 wherein the amount of HCl added to the brine feed solution is in an amount of up to about 20 weight percent HCl based on the weight of chlorine produced by the cell, said HCl addition being in an amount commensurable with the back migration of the hydroxyl ion from the catholyte compartment to provide a pH in the anolyte compartment of about 2 to 3.

18. The process of claim 17 wherein the caustic concentration in the catholyte compartment of the cell is increased by lowering the hydrostatic head of anolyte liquor within the anolyte compartment and increasing the amount of HCl added to the brine to provide an anolyte pH of about 2 to 3.

19. A process for increasing the caustic concentration of cell liquor in a chlor-alkali diaphragm cell comprising feeding to the anolyte compartment of said chlor-alkali cell a nearly saturated solution of brine while imposing a decomposition voltage across the electrodes of said cell, said brine feed solution being acidified with HCl, feeding said solution at a rate in excess of the amount which flows through the diaphragm into the catholyte compartment of the cell, adjusting the hydrostatic head of the anolyte liquor to lessen the flow rate through the diaphragm of said cell, regulating the HCl acidification of the brine to produce an anolyte pH below about 4, withdrawing the excess brine feed solution from the anolyte compartment, resaturating said withdrawn solution with salt and returning the resaturated brine solution to the anolyte compartment of the cell.

20. The process of claim 19 wherein the hydrostatic head within the anolyte compartment of the cell is reduced to lessen the flow through the diaphragm and thereby increase the concentration of caustic within the catholyte compartment.
